UNITED STATES PATENT OFFICE.

JESSE B. HAWLEY, OF WILMETTE, ILLINOIS.

DESIGN FOR A SOUND-AMPLIFYING HORN.

Application filed June 16, 1923. Serial No. 6,516. Term of patent 14 years.

To all whom it may concern:

Be it known that I, JESSE B. HAWLEY, a citizen of the United States, residing at Wilmette, Illinois, have invented a new, original, and ornamental Design for Sound-Amplifying Horn, of which the following is a specification, reference being made to the drawing forming a part thereof.

The annexed drawing is a perspective view of my new sound amplifying horn.

I claim:

The ornamental design for a sound amplifying horn as shown.

JESSE B. HAWLEY.
